A.P. Bertolucci

BY *Henry J. Webster*
ATTORNEY

UNITED STATES PATENT OFFICE.

ANTONIO P. BERTOLUCCI, OF SACRAMENTO, CALIFORNIA.

TILE ROOFING.

Application filed November 11, 1925. Serial No. 68,314.

This invention relates to improvements in tile roofing, my principal object being to provide a roofing of this character constructed of a number of different elements 5 arranged to be associated with each other to form a complete roof, and so constructed that when the elements are placed in position, an absolutely water tight roof will be formed. 10 Another object is to provide roofing members of such a nature that skilled labor is not essential in placing or assembling a roof. 15 A further object of the invention is to produce a simple and inexpensive device and yet one which will be exceedingly effective for the purpose for which it is designed. 20 These objects I accomplish by means of such structure and relative arrangement of parts as will fully appear by a perusal of the following specification and claim.

In the drawings similar characters of reference indicate corresponding parts in the several views:

Fig. 1 is a front view of a section of roofing, certain of the arch members being removed or broken out to illustrate various features of arrangement.

Fig. 2 is a transverse section on the line 2-2 of Fig. 1.

Referring now more particularly to the characters of reference on the drawings the numeral 1 denotes a plurality of flat rectangular members 1 from the body of the roof along the lower edges thereof.

Flanges 2 of any desired and uniform height throughout extend upwardly of the members 1 along the sides but not along the ends thereof, so that each member practically forms a wide shallow trough. When assembling a roof these members are laid first, but abutted closely against each other, and being supported along adjacent side edges by the usual rafters 3 and attached thereto in any suitable manner, as by nailing. Only a single row of these members is used.

Beyond such members other flat members 4 are employed and form the major portion of the body of the roofing. These members 50 are preferably the same length as the members 1 but are slightly tapered from end to end as shown. By so doing it will be seen that while one end of such members may overlap and rest on the corresponding members 1 between the flanges 2 thereof, the

other end of said members 4 will be the same width as the members 1, to receive the adjacent narrow end of the members 4 in the next row and so on.

The members 4 also have flanges 5 along 60 their side edges corresponding to the flanges 2 on the members 1.

It will therefore be evident that if these various members are laid at a certain slant with their lower ends overlapping the members in the rows below a reasonable distance, 65 water cannot leak between the different rows longitudinally of the roof. All water falling on these members will flow down to the lower ends of the members 1, there to 70 drop onto the ground, or to be received into a gutter, as may be desired.

Water would however leak between the members along their sides or transversely of the roof if some means were not employed to prevent this. I therefore provide inverted troughs or arch members to cover the abutting side edges and flanges of the different flat roof elements. For the edges of the members 1 the arches 6 may have 80 parallel sides. These arches rest on adjacent members 1 inwardly of the flanges 2 and of course straddle the latter, extending from the outer edges of said members to the overlapping lower edges of the adjacent 85 row of members 4. The outer ends of these arches may be filled with grout as at 7 to bind the same to the members 1.

The arch members 8 to cover the diverging edges of adjacent members 4 have a 90 transverse taper from end to end corresponding to the angle of divergence of said edges.

These arches also rest on the flat portions of the members 4 inwardly of the flanges 5 95 and straddle the same. They are also arranged to overlap the arches 6 a certain distance and to extend thence to abut against the overlapping lower edges of the next row of members 4. Similarly the 100 arches for the next row of members 4 overlaps the upper ends of the arches 8 of the row below, and extend thence to the overlapping edges of the next row of members 4 thereabove. The arches 8 being tapered, not only enables the sides of the same to be parallel to the adjacent flanges 5, so as to prevent displacement of the arches relative to the flanges; but enables the lower end of the arch to properly over, 110

lap the upper end of the arch in the row below. This arch arrangement, as will be evident, provides an efficient water tight covering for the joints between the body members of the roof, and in connection with the overlapping of the arches themselves and the overlapping of the body members with each other, insures that all joints in the entire roof will be covered and therefore rendered leak-proof.

The material of which all roof elements are made is preferably a suitable clay product, such as is commonly used for tile making but cement, concrete, or other material may be used if desired.

It will be noted that the first or rectangular row of tile is the only one which is necessarily secured to the rafters. In the subsequent rows, the tile being tapered from end to end and fitting into each other and into the tile of the first row, as shown and described, do not need such securing means, since they wedge into each other and cannot slip down to completely overlap the tile of the adjacent rows.

It will also be evident that the arches, without any securing means, cannot slide along the flat tile or along each other, since the diverging flanges on the flat tile form a wedge shaped structure preventing such movement of the arches therealong and the tapered fit of the arches with each other

prevents longitudinal movement of the tile on each other.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention, what I claim as new and useful and desire to secure by Letters Patent is:

A tile roofing structure comprising tile laid in courses, each tile of each course comprising a flat tapered member, upturned edges along and following the tapered side edges of the tile, the narrow end of the tile in one course being wedged between the flanges of the wide end of the tile in an adjacent course; and an arch member overlapping each pair of adjacent flanges, each arch member tapering from end to end, the wide ends of the arches in one course wedging over the narrow ends of the arches in the adjacent course.

In testimony whereof I affix my signature.

ANTONIO P. BERTOLUCCI.
